UNITED STATES PATENT OFFICE.

CHARLES B. MOORE, OF EVANSTON, ILLINOIS, ASSIGNOR, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,039.

Specification of Letters Patent.

Patented May 4, 1915.

Application filed December 18, 1911. Serial No. 636,337.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has special reference to refractory baffles or arches for the fireboxes of locomotive boilers.

The general objects of my invention are to provide an improved refractory arch which may be easily and quickly installed in locomotive fireboxes; to provide an arch which shall be comparatively light in weight and of low cost; to provide an arch which shall be easy to repair and parts of which may be readily removed to afford easy access to the firebox sides and flue sheet; and to provide an arch which in a practical sense shall assist in commingling, admixing and igniting the firebox gases and other combustibles.

My invention consists in the several improvements, the various constructions, and the combinations and relations of parts hereinafter set forth and particularly pointed out in the appended claim; and will be readily understood upon reference to the accompanying drawings.

In these drawings, which form a part of this specification, Figure 1 is a plan sectional view of a locomotive firebox equipped with a refractory arch illustrating one embodiment of my invention; Fig. 2 is a vertical, transverse sectional view of the firebox on the line 2—2 of Fig. 1; Fig. 3 is a longitudinal central sectional view on the line 3—3 of Fig. 1; Fig. 4 is a detail transverse sectional view on the line 4—4 of Fig. 3.

My invention is capable of embodiment in arches of various forms and different locations in the firebox of a locomotive.

A so-called front arch is an arch or arched body located in the firebox and adapted to baffle or deflect the firebox gases in their passage from the grate to the flues. It occupies an inclined position, its forward end in abutment with or located close to the lower portion of the flue sheet and the arch itself extending rearwardly and upwardly therefrom.

I build my arches of a number of indi-

vidual bricks of a size that may be handled easily and that may be passed through the fuel door. The individual arch bricks are formed to present a number of gas deflecting surfaces which aid greatly in intermingling the gases and deflect the more solid fuel particles back to the fuel bed.

The various structures illustrated in the drawings have the features above mentioned. A locomotive firebox as shown, consists of a flue sheet 2, side sheets 3, 3, a crown sheet 4 and a rear sheet 5. A grate 6 is provided in the lower part of the firebox. Flues 7 lead forward from the flue sheet. The rear sheet is provided with a fuel door or opening 8. The firebox itself is positioned within the shell 9 of the locomotive boiler, and I employ therein two water circulating arch tubes 10, the same extending from the lower portion of the flue sheet to the upper portion of the rear sheet. On account of the closeness of the grate to the flues, in the boiler illustrated, the tubes 10 are quite widely separated, in fact, they are separated as far as possible leaving only sufficient room between the tubes and respective side sheets to permit the necessary repairing of the side sheet stay bolts.

I build my preferred form of arch of two brick patterns or forms *a* and *b*. The bricks *a* form the central or main portion of the arch, a plurality of pairs being used which rest upon and are arched between the tubes 10. These bricks abut midway between the tubes and are provided with complementary interlocking tongues 11 and grooves 12 upon their abutting ends. These interlocking tongues and grooves in combination with the end or locking bricks *b* maintain the bricks *a* in their proper positions once they have been placed. The tongues and grooves prevent the relative vertical movement of the abutting ends and the locking bricks *b* prevent lateral separation of the bricks *a*. In addition to the above, the weight of the bricks *a* assists in retaining them in interlocked condition and hence in their proper relative position in the firebox.

I prefer to make the bricks *a* practically as wide as possible consistent with the other requirements, to the end that the number of individual bricks or pieces in the arch will be as few as possible, to facilitate the rapid construction of these arches. The arch

bricks *a* are provided with a plurality of gas mixing cavities or pockets *a'* in their under sides which not only lighten the bricks, making it possible to form them of larger area than if they were solid and yet not be too heavy for convenient handling, but also provides the arch with a plurality of gas deflecting surfaces or walls arranged at different angles which enhance the desired effect of intermingling the gases and deflecting the fuel particles downward to the fuel bed. These pockets result in the bricks *a* being provided with comparatively narrow or thin marginal edges or ribs *a''*, the longitudinal marginal ribs being joined by the middle partition or wall *a''*. This wall divides the pockets *a'* into smaller pockets and strengthens the longitudinal marginal edges *a''* besides providing the brick with an additional gas deflecting surface. The length of the bricks *a* is determined by the spread of the tubes 10, the combined length of the bricks forming a pair being considerably more than the distance apart of the centers of the tubes, so that when the bricks are placed in position they will rest against each other after the manner of a gable roof and sustain each other in position.

The bricks *b* extend in line with the bricks *a*, that is, downwardly, and fill in between their ends and the side sheets 3 of the firebox. The bricks *a* and *b* abut above the tubes 10, so that they each find a resting place thereon and the outer ends of the end or locking bricks *b* are supported upon studs or lugs 3' provided upon the side sheets below adjacent tubes 10. The bricks *b* are preferably of the same width and depth as the bricks *a* and in a sense complete the partial arch formed by the bricks *a*. They are preferably provided with gas mixing pockets *b'* in their under sides similar to the pockets *a'* in the bricks *a* and which serve the same purpose.

To make the arch as a whole substantial and retain it securely in position, the locking bricks *b* are preferably beveled on their outer ends to abut the side sheet with substantially their whole area. The bricks *b* being inclined downwardly in substantial alignment with the span or arch bricks *a*, the weight of the arch is mainly carried by the side sheets through the medium of the studs 3' and to this extent the tubes 10 are relieved of the thrust of the bricks *a* making this form of construction very desirable for fireboxes having but two arch tubes. Another desirable feature of this form of

construction is that the downwardly extending key or locking bricks *b* reduce the firebox space below the arch or below the tubes. This is particularly advantageous in fireboxes that are comparatively high or in those of ordinary height in which the arch tubes rise comparatively near to the crown sheet.

In building or installing arches which embody my invention, I place the lowermost pair of locking bricks *b* in position, resting upon the tubes 10 and upon the respective side sheet studs 3', and properly space them from the flue sheet by means of the refractory spacing bricks or blocks *C*, which are supported and held in place by the tubes 10. Then I complete the first span 75 by placing the first or lowermost pair or span of the bricks *a* in position, abutting the bricks *b* substantially above the tubes 10, upon which the bricks *a* rest and by which they are supported and having their abutting ends leaning against the flue sheet. Then I build the second span in like manner, placing the bricks thereof in position upon the tubes and resting against the respective bricks of the first span. The openings *d* between the lower front corners of the arch and the flue sheet serve to allow the cinders and ashes which collect upon the top or back of the arch, to return to the fuel bed.

Having thus described my invention, I claim as new and desire to secure by Letters Patent:

A locomotive boiler fire box as described, in combination with two longitudinally inclined water-circulating arch-tubes adjacent to opposite side sheets of the box, studs upon said side sheets substantially below respective tubes, a row of downwardly and outwardly inclined refractory bricks between each tube and adjacent side sheet, each said brick having its inner end upon the tube and its outer end supported by a said stud or studs, an arch body formed of two longitudinal rows of refractory bricks arched upon and between said rows of bricks and each of the body bricks having in its under side two gas mixing pockets separated by a strengthening wall or partition.

In testimony whereof, I have hereunto set my hand this 5th day of December, 1911, in the presence of two subscribing witnesses.

CHARLES B. MOORE.
